NIGHT LAMP

Lee Retta Haddox, Connell, Wash.

Application October 10, 1955, Serial No. 38,309

Term of patent 14 years

(Cl. D48—20)

I claim:

The ornamental design for a night lamp, as shown.
